CONTROL FOR DOUBLE DOORS

Thomas H. Sheehan, Jr., Detroit, Mich.

Application June 5, 1946, Serial No. 674,568

4 Claims. (Cl. 268—62)

1

This invention relates to a control for double doors and more particularly to a control for double doors which synchronizes the opening and closing of the doors and which holds the doors in either fully opened or fully closed position. My invention is particularly useful in connection with double garage doors which swing on vertical axes.

It is an object of this invention to produce a simple and efficient mechanism which causes two swinging doors to operate as one and which automatically holds the doors in either open or closed position.

Fig. 1 is a horizontal section showing my mechanism applied to double garage doors.

Fig. 2 is a section along the line 2—2 of Fig. 1. Referring more particularly to the drawings, I have shown doors 1 and 2, which are hinged to door posts 3 and 4 by hinges 5 and 6, so that they swing about a vertical axis. An L-shaped link 7 is pivoted as at 8 to hinge bracket 9 which is secured by screws or otherwise affixed to the inside face of door 2.

Link 7 has a long leg 10 and a short leg 11. Link 7 lies generally in a plane perpendicular to the plane of doors 1 and 2 and leg 10 from its point of pivoting 8 extends inwardly from the inner faces of doors 1 and 2 when closed and leg 11 extends generally from leg 10 in a direction toward the inner face of the door. The end of link 7 is pivoted as at 12 to bracket 13 which is secured by screws or otherwise affixed to the inside face of door 1.

A tension spring 14 has one end connected to bracket 13 at point 15 and the other end connected to link 7 at point 16. When doors 1 and 2 are closed it will be seen that points 15 and 16 are to the right of pivot 12 and when the doors are open, as shown in the dotted lines, points 15 and 16 are to the left of pivot 12. In other words, tension spring 14 is an over-center type of spring which, when the doors are closed, acts between link 7 and bracket 13 to apply a force thereto which tends to hold doors 1 and 2 closed and when the doors are open the force of spring 14 applied at the same points tends to hold doors 1 and 2 open.

Further, it will be seen that movement of either door 1 or 2 either in opening or closing direction will, through link 7 and bracket 13, simultaneously transmit a like opening or closing motion to the other door. In other words, the opening and closing of doors 1 and 2 are synchronized.

It will be noted that the included angle A be-

2

tween leg 11 and bracket 13 is less than 180° when the doors are closed and when the doors are open angle A' is greater than 180°. To state this same set of facts differently: the angle A made by leg 11 and bracket 13 opposite spring 14 is less than 180° when the doors are closed and the angle B between leg 11 and bracket 13 opposite spring 14 when the doors are open is also less than 180° and substantially the same as angle A, but the angles A and B are positioned on opposite sides of pivot 12.

It will be noted that the effective length of link 7 is the distance between pivot 12 and pivot 8 and that the effective length of link 7 plus the length of arm 13 should preferably be at least equal to, or greater than, the width of the door opening between hinges 5 and 6 so that the doors can swing fully open to clear the door opening.

20 I claim:

1. In combination a pair of doors pivoted on opposite parallel supports and arranged to swing in unison in opposite directions so as to be positioned in substantially the same plane when closed, an arm fixed to the inside face of one door and projecting in a direction inwardly from the inside face thereof when the door is in the closed position, a link pivoted at one end to the inside face of the other door and at the other end to said arm at a point spaced inwardly from the inside face of said doors when closed, said link having an integral portion thereof offset from the pivot between said link and arm in a direction inwardly of and away from the inner face of the doors when closed, and resilient means acting between the offset portion of said link and the door to which the rigid arm is connected on one side of the pivot between said arm and link when the doors are closed whereby the resilient means tends to hold said doors closed, said resilient means in the opening of said doors passing to the opposite side of said pivot whereby the force exerted by said resilient means between the link and the door to which the arm is secured tends to hold said doors open.

2. In combination with a pair of doors pivoted on opposite parallel supports and arranged to swing in unison in opposite directions so as to be positioned in substantially the same plane when closed, an arm fixed to the inside face of one of said doors and extending in a direction inwardly from the inside face thereof when the door is in the closed position, a link having one end pivoted to the inside face of the other of said doors and the other end pivoted to the end of

said arm, the said link being substantially in the shape of an L lying substantially in a plane perpendicular to the plane of the doors with the corner of the L positioned so that the pivot between said arm and link lies between the corner of the L link and the said door, and a spring connected to the door at one end and to the corner of the L link at the other, said spring lying at one side of the pivot between the arm and the link when the doors are in closed position and being arranged to pass to the opposite side of said last named pivot in opening the doors.

3. In combination a pair of doors pivoted on opposite parallel supports and arranged to swing in unison in opposite directions so as to be positioned in substantially the same plane when closed, a rigid support fixed to the inside face of one of the doors and projecting in a direction inwardly of the inside face thereof when the door is in the closed position, a rigid link pivotally connected to the other of said doors and on the inside thereof, a pivotal connection between said rigid link and the rigid support at a point spaced inwardly of the inner faces of the doors when closed, said rigid link having an integral portion offset from the pivotal connection between the link and the door in a direction inwardly of and away from the inner face of the door, and resilient means connecting said offset portion of the link and the door carrying the fixed support on opposite sides of said pivotal connection, the said pivotal connection between

the support and link being positioned relative to the plane of the door between the connection between the said resilient means and the offset portion of the link and the connection between the resilient means and the door.

- 5 4. The combination as set forth in claim 3 wherein the rigid support is positioned adjacent the axis of swinging of the door which carries the support and the resilient means passes from 10 one side of the said pivotal connection between the link and the support to the other when the doors are swung from closed to open position 15 whereby swinging movement of the one door causes simultaneous swinging of the other door and the resilient means acts to maintain the doors open and closed when swung to either of said positions.
